 General Machinery Corporation, Hamilton,
 Ohio, a corporation of Delaware

Application April 30, 1934, Serial No. 723,133

5 Claims. (Cl. 113—38)

This invention relates to power presses, and more particularly to presses for drawing or forming sheet metal or the like.

One object of the invention is the provision of a power press having a work forming slide which is alternately operated by a high speed driving connection to a power source and a low speed driving connection to a power source to obtain a comparatively low speed of movement of the slide during the work forming or drawing part of the cycle of press operations.

Another object of the invention is the provision of a press for drawing or working metal, having a plurality of driving connections including a plurality of clutches which are automatically operated in timed relation with the slide so as to connect the driving motor alternately through a high speed and a low speed driving connection to a power source.

Other objects and advantages of the invention will be apparent from the following description, the appended claims and the accompanying drawings, in which—

Fig. 1 is a front elevation of a power press embodying the present invention, a part of the lower portion of the press being omitted;

Fig. 2 is a side elevation of the upper part of the press;

Fig. 3 is a section on the line 3—3 of Fig. 2;

Fig. 4 is a diagrammatic showing of the electrical control system; and

Fig. 5 is a partly diagrammatic view of the control switches and their operating cams.

Conventional drawing presses are driven from an operating shaft which rotates at a uniform rate of speed, for example at the rate of about six strokes per minute which has been found to be about the most economical rate for certain uses. If a higher rate of speed is employed it is found that the number of broken stampings, due largely to high drawing speed, is unduly increased. The breakage can be reduced by lowering the number of strokes per minute but then the total production in any given time period will also be reduced. In accordance with the present invention, however, the operating shaft by means of which the movable slide is driven, is so operated that the speed of the plunger is materially slower during the drawing part of a cycle of press operations in order that a comparatively high number of strokes per minute is attained without correspondingly increasing the speed of the drawing operation itself.

The press may be of any suitable character having a movable slide which carries the die

for drawing or otherwise forming the work, and may be equipped with the usual air pressure controlled slide and have any desired number of mechanically moved slides for serving as blank holding members, forming members, etc. As herein shown the press is provided with a plurality of mechanically operated upper slides 11 and 12 and the mechanically operated lower slide 42, which are moved in timed relationship as more fully set forth in my prior United States Patents No. 1,768,503 and No. 1,967,464.

Referring more particularly to the drawings, 10 designates generally the frame of the press in which the slides 11 and 12 are mounted for reciprocatory movement so that the slide 11 may descend first and dwell for a period of time while the die carried by the slide 12 is effective in drawing the metal. The slides 11 and 12, as shown, are operated by a system of toggle levers, both having a dwell period by reason of the relative arrangement of the centers of the various operating parts.

Rotatably mounted in an upper portion of the press frame is a power operated driving shaft 13. This shaft is rotated by two gears 14 and 15 each of which meshes with a pinion 16 provided at opposite ends of a shaft 18 which also carries a gear 17. The gear 17 meshes with the driving pinion 19 provided on a transverse shaft 20. This shaft 20, as will be more fully described, is operated at comparatively high speed or at comparatively low speed from an electric motor 21.

The gears 14 and 15 are each provided with an eccentric stud 25 which is connected by an arm 26 to a vertically reciprocatory slide block 27, the two slide blocks, one at either side of the frame, being connected to the four rock shaft extensions 28 which are rigid with the toggle arms 30, the latter being pivotally connected to the toggle links 31 and operating the inner slide 12. The connection between the crank shaft 13 and the blank holding slide 11 is effective through toggle links 32 which are connected to toggle arms rigid with the two rock shafts 33 which are operated from the slide 34 driven by operating means connected to the crank throw 36, as more fully explained in my prior patent and patent application referred to above.

During the time the slide 12 is dwelling it may itself serve as a blank holder together with a slide 11 while the work is being operated upon by a die which is mounted for reciprocatory movement in a lower portion of the press. Such lower die may be operated by means of the lower die

carrying slide designated generally 42. Slide 42 is guided for vertical movement, its opposite ends being connected to operating rods 48, the upper ends of which are formed as eccentric straps 49 engaged with the cylindrical surfaces 40 that are eccentrically provided at opposite ends of the operating shaft 13.

The motor 21 is connected by means of a driving belt 50 or the like to a flywheel 51 which 10 is freely rotatable on antifriction bearings 52 provided on an operating shaft 53, as shown in Figs. 1 and 3. The shaft 53 is rotatably supported in bearing portions 54 of the frame, one end of the shaft being fixed to a gear pinion 55 which 15 meshes with gear 56 fixed on one end of shaft 20. The flywheel may be placed in driving connection with shaft 53 by means such as the magnetic clutch 57. As herein shown the clutch comprises a flexible plate member 58 secured to the 20 shaft 53 and adapted to be held between the driving plates 59 and 60 when the clutch energizing coil 61 is supplied with electric current. The clutch energizing supply comes in through wires 62 connected to conductor rings 63 engaged 25 by brushes 64. When the clutch is engaged, the flywheel 51 and the shaft 53 move at the same speed of rotation, and the operating shafts 20 and 13 are driven at a comparatively low speed suitable for metal drawing operations.

30 Rotatably mounted at the other end of the shaft 53 is a sleeve 66 which is rotatably mounted in a bearing portion 54 of the frame. On the outer end of the sleeve is fixed a gear 68 that meshes with a gear 69 fixed on shaft 20. The 35 sleeve, which can rotate freely on the shaft 53, may be coupled up to the flywheel 51 by means of a magnetic clutch 70 which is generally similar in construction to the magnetic clutch provided on the opposite end of the flywheel.

40 At one end of the shaft 20 is a brake wheel 71 adapted to be engaged by a brake shoe 72 under the action of a spring 73. The spring is compressed and the brake shoe 72 moved to a released position by means of an electro-magnet 45 74 when the electro-magnet is energized.

The two clutches 57 and 70, and the magnetic brake, are automatically controlled in proper timed relation with the movements of the slide by means of a switch system that has been illustrated diagrammatically in Figs. 4 and 5. This switch system includes a sprocket gear 76 driven by a sprocket chain 77 from the crank shaft 13, the sprocket gear being connected so as to operate at the same speed as the crank shaft 13. 55 Three cams 78, 79 and 80 are fixed to the shaft 81^a on which the sprocket gear 76 is provided, and serve respectively for the control of switches 81, 82 and 83. These switches are provided at a suitable location on the frame in a cam and 60 switch box. When the slide 12 is at its uppermost position, the switch 81 is closed and remains closed until the slide has descended. At the start of a cycle of operations, with the slide in its uppermost position, the switches 82 and 65 83 are open.

The power source S, as shown in Fig. 4, is connected through stop switches 85 which are normally closed but which may be operated by the attendant in case of emergencies. In series with 70 the switches 85 are a plurality of starting switches 86 two of which are closed by the two hands of one attendant while the other two are closed by the hands of the second attendant when a cycle of operations is to be started. Before 75 these switches are closed, however, one of the

operators has moved a drum type switch 87 so as to interconnect the points a, b, c and d together and to interconnect points e and f together. With the drum type switch in position for starting operations, and with the several switches 86 closed, current is supplied from one side of the line S to a relay 84 which when energized closes the connection from the line S to one side of the magnetic clutch elements 61 and 93, and to one side of the brake winding 74. Current also flows through the closed switch 81 to a relay 88 which is energized so as to complete a circuit from one side of the line S through wire 89 to the coil 61 of the magnetic clutch 57. The circuit is thus completed through winding 61 and the magnetic clutch 57 connects the slide through the low speed gear drive to the flywheel.

The shaft 13 is therefore operated at comparatively low speed, suitable for press forming operations, switch 81 remaining closed and switch 83 closing at about 90 degrees, rotation of the crank shaft. When switch 83 closes it short circuits the manually operated push buttons or switches 86 so that the operators can remove their hands and current will continue to be supplied through switch 83 to the relay 88. When the slide reaches its lower limit of movement, and after it has completed its metal forming operation, the switch 81 opens and at the same time switch 82 closes. When switch 81 opens the winding 61 of the magnetic clutch 57 is deenergized, but the closing of the switch 82 has energized relay 90 and completed a circuit from one side of the line to a lead 91 which is connected to the winding 93 of magnetic clutch 67. The flywheel is therefore connected through the high speed drive gearing including the gears 68 and 69 so as to move the slide at comparatively high speed as the slide moves up away from the work. Just before the slide reaches its upper limit of travel, the cams 79 and 80 are effective on the switches 82 and 83 to open both of these switches. This deenergizes the magnetic clutch 57. At the same time this happens, the switch 81 is again closed, but the winding 61 of the magnetic clutch 57 is not energized since the push buttons 86 are open and switch 83 has been opened. When the switch 83 opens it interrupts a flow of current through contact c and lead 95 and deenergizes a relay 96 which was closed to energize the brake releasing winding 74 when the push buttons 86 were first closed by the operators. The deenergization of the winding 74 causes the brake to be applied, thus stopping the press ready for a second cycle.

When setting dies it is necessary to move the plunger a small amount at a time and to provide for such operation, or "inching" as it is termed, the drum switch 87 is rotated to interconnect points f, g and h, which connects the inching switch 98 ahead of the starting buttons 86 and ahead of the cam operated switch 83. The inching switch 98 may be closed by the operator so as to connect one side of the line directly through a lead 99 to energize the relay 88 and through a lead 100 to energize the relay 84 in order to energize the magnetic clutch 57.

It will now be apparent that when the operator so desires, he can start the press in operation by closing the push buttons 86. The press will then start moving at comparatively low speed suitable for metal drawing, and will continue to move at such low speed until the metal forming is completed. The magnetic clutches will then be automatically operated so that one is engaged and the other is disengaged in order to cause an in-

crease of press speed during the non-effective part 5 of the cycle of operations while the slide moves upwardly. At the end of a cycle of operations the press is automatically stopped by means of the brake. Inasmuch as the non-effective parts of the cycle of press operations are carried out quickly the number of strokes per minute of the press 10 can be considerably higher than the conventional speed of operation while still maintaining a suitable low speed of operation during the work drawing parts of the cycle.

While the form of apparatus herein described constitutes a preferred embodiment of the invention, it is to be understood that the invention 15 is not limited to this precise form of apparatus, and that changes may be made therein without departing from the scope of the invention which is defined in the appended claims.

What is claimed is:

- 20 1. A press comprising a frame, a metal drawing slide reciprocably mounted therein, an operating shaft for said slide, mechanism positively connecting said slide and shaft for timed operation throughout a complete revolution of said shaft, 25 drive means for operating said shaft at high speed, drive means for operating said shaft at low speed, a motor for operating said drive means, and means operable in timed relation with said shaft for engaging said motor with said drive 30 means to obtain low speed movement of said shaft and said slide during the metal drawing part of a cycle of press operations and high speed movement of said shaft and said slide after the metal drawing part of a cycle.
- 35 2. A press comprising a frame, a metal forming slide reciprocably mounted therein, a rotatable operating shaft for said slide, mechanism positively connecting said slide and shaft for timed operation throughout a complete revolution of said shaft, a motor, a high speed operating connection between said motor and said shaft including a clutch, a low speed operating connection between said motor and said shaft including a second clutch, and means operable in timed 40 relation with said shaft for alternately engaging said clutches to obtain low speed press operation throughout the period in the press cycle while the slide moves in one direction and to obtain high speed press operation throughout the period in the press cycle while the slide moves in the other direction.
- 45 3. A drawing press comprising a frame, a slide reciprocably mounted therein, a rotatable operating shaft for said slide, mechanism positively

connecting said slide and shaft for timed operation throughout a complete revolution of said shaft, a motor, drive means for operably connecting said motor to said shaft to obtain low speed movement of said shaft, a second drive means for operably connecting said motor to said shaft to obtain high speed movement of said shaft, timing means movable in timed relation with said shaft, and a switch system controlled by said timing means and automatically controlling the 10 connection between said motor and said drive means, said timing means and switch means providing for low speed operation of the slide during the drawing part of a cycle of operations and providing for high speed operation of said slide 15 while the slide is moving away from the work.

4. A press comprising a frame, a metal drawing slide reciprocably mounted therein, an operating shaft for said slide, mechanism positively connecting said slide and shaft for timed operation 20 throughout a complete revolution of said shaft, a motor, gearing for operating said shaft at low speed, a magnetic clutch for coupling said gearing to said motor, a second gearing for operating said shaft at high speed, a second magnetic clutch 25 for coupling said motor to said second gearing, means operable in timed relation with said shaft for automatically controlling said clutches to obtain low speed movement of the slide during 30 the work forming part of a press cycle and high speed movement of the slide after the work forming part of a press cycle.

5. A drawing press comprising a frame, a blank holder slide and a metal drawing slide mounted for reciprocatory movement in said frame, a 35 rotatable operating shaft, mechanism positively connecting said slides and said shaft and providing a dwell in the operation of the blank holder slide in fixed timed relation with respect to the movements of the drawing slide, a motor, drive 40 means operably connecting said motor to said shaft for operating said shaft at a comparatively low speed, drive means operably connecting said motor to said shaft for operating said shaft at comparatively high speed, and means operable in 45 timed relation with said shaft for alternately engaging said motor with said drive means to obtain a comparatively low speed movement of said drawing slide throughout the metal drawing part of a cycle of operation and to obtain comparatively high speed movement of said slides while 50 moving away from the work piece after the completion of the drawing operation.

ARTHUR A. BYERLEIN.
